(57) **CLAIM**

The ornamental design for a two-part cradle for mobile phone, as shown and described.

DESCRIPTION

FIG. 1 is a front plan view of a two-part cradle for mobile phone according to the design of the invention, with only the phone holder part of the cradle being visible in this view. FIG. 2 is a top end view of the design shown in FIG. 1. FIG. 3 is a right side view of the design shown in FIG. 1. FIG. 4 is a bottom end view of the design shown in FIG. 1. FIG. 5 is a left side view of the design shown in FIG. 1. FIG. 6 is a rear plan of the design shown in FIG. 1. FIG. 7 is a front-top-right perspective view of the design shown in FIG. 1.

FIG. 8 is a front-top-left perspective view of the design shown in FIG. 1.

FIG. 9 is a top plan view of the base part of the two-part mobile phone cradle of FIG. 1.

FIG. 10 is a top end view of the base part shown in FIG. 9. FIG. 11 is a right side view of the base part shown in FIG. 9.

FIG. 12 is a bottom end view of the base part shown in FIG. 9.

FIG. 13 is a left side view of the base part shown in FIG. 9. FIG. 14 is a rear plan view of the base part shown in FIG. 9.

FIG. 15 is a front-bottom-left perspective view of the base part shown in FIG. 9.

FIG. 16 is a front-bottom-right perspective view of the base part shown in FIG. 9.

FIG. 17 is a front-top-right perspective view of the base part shown in FIG. 9.

FIG. 18 is a top end view of the phone holder part of the two-part mobile phone cradle of FIG. 1.

FIG. 19 is a right side view of the phone holder part of the two-part mobile phone cradle of FIG. 1.

FIG. 20 is a bottom view of the phone holder part of the two-part mobile phone cradle of FIG. 1.

FIG. 21 is a left side view of the phone holder part of the two-part mobile phone cradle of FIG. 1.

FIG. 22 is a rear plan view of the phone holder part of the two-part mobile phone cradle of FIG. 1.

FIG. 23 is a front-top-right perspective view of the phone holder part of the two-part mobile phone cradle of FIG. 1; and,

FIG. 24 is a front-bottom-left perspective view of the phone holder part of the two-part mobile phone cradle of FIG. 1. The two individual components have been shown separately in FIGS. 9-24 for convenience of illustration.
